(57)

CLAIM

The ornamental design for a container lid, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top perspective view of a first embodiment of a container lid, showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a cross-sectional view thereof taken along line 7-7 in FIG. 5;

FIG. 8 is a top perspective view of a second embodiment of a container lid, showing the claimed design;

FIG. 9 is a bottom perspective view thereof;

FIG. 10 is a front view thereof;

FIG. 11 is a rear view thereof;

FIG. 12 is a left side view thereof;

FIG. 13 is a right side view thereof; and,

FIG. 14 is a cross-sectional view thereof taken along line 14-14 in FIG. 12.
